US0D1015554S

(12) **United States Design Patent** (10) **Patent No.:** **US D1,015,554 S**
(45) **Date of Patent:** **** Feb. 20, 2024**

(54) **HOT WATER BOTTLE COVER**

(71) Applicant: **Shenzhen Zortek Innovative Technology Co., Ltd.**, Shenzhen (CN)

(72) Inventor: **Jiajin Zeng**, Shenzhen (CN)

(73) Assignee: **Shenzhen Zortek Innovative Technology Co., Ltd.**, Shenzhen (CN)

(**) Term: **15 Years**

(21) Appl. No.: **29/789,791**

(22) Filed: **Oct. 18, 2021**

(51) **LOC (14) Cl.** **24-01**

(52) **U.S. Cl.**
